UNITED STATES PATENT OFFICE.

FRANK J. LYNCH, OF HILLSIDE, NEW JERSEY, ASSIGNOR TO THE SUN TUBE CORPORATION, OF HILLSIDE, NEW JERSEY, A CORPORATION OF NEW JERSEY.

APPARATUS FOR EXTRUDING CAPS.

Application filed March 29, 1928. Serial No. 265,687.

This invention relates to the formation of caps for collapsible tubes and the like, and particularly the formation of caps by extrusion, the object being to provide a desirable form of internally-threaded cap with a minimum amount of material.

Another object of the invention is to provide an improved die and also improved method of operation for not only forming 10 the cap but for ejecting the same after having been formed.

In the accompanying drawings—

Figure 1 is a longitudinal vertical sectional view through a pair of dies and associated parts disclosing how a cap may be formed;

Figure 2 is a view similar to Figure 1 showing the parts separated with the cap ejected;

Figure 3 is a perspective view of the finished cap.

Referring to the accompanying drawing by numerals, 1 and 2 indicate dies, die 1 being preferably stationary and die 2 preferably movable. These dies may be operated either vertically or horizontally, but as shown in the drawing they are operated horizontally.

When a cap is to be formed a slug of the desired size is placed in the cavity 3 of die 2 by any desired means, and the plunger 4 moves down to the position shown in Figure 1. Die 2 with its slug is then forced against die 1 and the slug will be extruded until it assumes the position shown in Figure 1. It will be noted that die 2 is provided with an annular portion 5 adapted to fit into the annular recess 6, while annular projection 7 of die 1 fits into the socket 3. Plunger 1 is provided with a shoulder 8 and with a threaded extension 9 of the same size as the threaded neck of the tube on which the cap is to be eventually mounted. The walls of socket 1 are preferably milled, so that when the cap has been completed, a milled surface 10 will be presented, as shown in Figure 3. This milled surface is on the flange 11 which merges into the top 12 of the cap which in turn merges into the internally-threaded body 13. By forming the cap in this manner the seam or finishing edge, if any, will be at the point 14. After the dies have come together and extruded or formed the cap, as shown in Figure 1, die 2 is backed off 55 to substantially the position shown in Fig-

ure 2, and in backing off moves out of contact with the milled surface 10. This may be readily done, as the threaded portion of plunger 4 holds the cap firmly in place. After die 2 has been backed off plunger 4 is 60 rotated so as to be unscrewed from the cap and the cap is at that time then held only by the friction of the body 13 against die 1, so that an ejecting plunger 15 may readily strike the cap and move the same to the 65 position shown in Figure 2. After the ejecting plunger 15 has been withdrawn the cap will drop by gravity to a desired point, and the operation may be repeated. It is to be noted that the wall 16 is slightly tapering, 70 so that the inner wall 17 on the cap will be tapering. This reduces the friction to a great extent, and as the outer part of the flange 11 is free, it will require but a small amount of power to push the cap out of engagement with die 1. By reason of this fact the top 12 may be made comparatively thin 75 throughout. The flange 11 may also be made comparatively thin, thus presenting an efficient and desirable cap with a minimum 80 material. Extra thickness in the top 12 has heretofore been necessary by reason of the power required to eject the finished cap but by the construction of the dies in the method used herein, this extra thickness is eliminated, as the friction is reduced to a minimum 85 and consequently the cap may be ejected with small effort.

What I claim is:—

1. A cap forming apparatus, including a 90 pair of dies, one die being formed with a centrally-disposed recess and an annular ring portion and the other die being formed with a central bore extending through the die, an annular recess for receiving said ring, 95 and a projecting ring adapted to fit into said recess, said recess being formed with milled walls, whereby when the dies come together for forming a cap the outer edge of the cap will be milled, and when the dies are separated the outer surfaces of the cap, except the body, will be out of contact with the dies and a shaft rotatably fitted into said bore, said shaft having a threaded portion at the end thereof of less diameter than the 100 bore, whereby when the dies come together a space will be provided for the body of the cap when formed.

2. An apparatus for forming by extrusion 105 an internally-threaded cap having a top 110

merging into a flange, said apparatus including a pair of co-acting dies and a plunger having a threaded end portion, said plunger being fitted into one of said dies when in opposite position, the die carrying the plunger having a bore for receiving the plunger and an annular groove surrounding the bore at one end thereof, said groove being spaced from the bore, whereby an ejecting ring will be presented, said ring on its outer surface being tapering, the other of said dies being formed with a socket having a ring around the socket, said ring fitting into said annular groove 1 but slightly spaced from said ring, whereby when a slug is in said recess and said dies are brought together, the slug will be extruded so as to surround the threaded part of said plunger and surround on three sides the ring formed on the die having the bore.

3. A structure for forming by extrusion an internally-threaded cap having a tubular body, a top therefor and a depending flange extending from the top and surrounding the body, said structure including a stationary die, a movable die and a plunger,

said stationary die having a bore extending therethrough and an annular recess surrounding the bore at one end but spaced therefrom, whereby a forming ring is provided around said bore, said plunger being positioned at said bore formed with a reduced threaded end extending to a point flush with the side surface of said ring, and the movable die being formed with a socket of slightly greater diameter and depth than said ring, the end of said movable die fitting into the said annular recess when in an operated position, whereby when a slug is placed in said recess and the movable die is moved to an operated position in respect to the stationary die, the slug will be extruded for forming a tubular body around said reduced threaded section, a radiating top extending over the side surface of said ring and a flange extending over the periphery of the ring.

Signed at Hillside in the county of Union and State of New Jersey this 21st day of March, A. D. 1928.

FRANK J. LYNCH.
